UNITED STATES PATENT OFFICE.

AMOS H. HAWLEY, OF NORWOOD, OHIO, ASSIGNOR TO INTERNATIONAL MONEY
MACHINE COMPANY, OF READING, PENNSYLVANIA.

ACCOUNTING-MACHINE HANDLE.

1,311,394.

Specification of Letters Patent. Patented July 29, 1919.

Original application filed March 31, 1917, Serial No. 158,923. Divided and this application filed September 24, 1917. Serial No. 192,985.

To all whom it may concern:

Be it known that I, AMOS H. HAWLEY, a citizen of the United States, residing at Norwood, in the county of Hamilton and 5 State of Ohio, have invented certain new and useful Improvements in Accounting-Machine Handles, of which the following is a specification, same being a division of my application Serial No. 158,923, filed March 10 31, 1917.

This invention has to do with accounting or registering machines of the crank handle operated type. The invention involves an improved connection between the crank handle and the main actuating shaft of the machine. At the present time a very common, and perhaps the most used type of connection between accounting machine operating shafts and handles, embodies a detent or 15 latch mounted on the handle and capable of interlocking with the shaft, an arrangement quite the same as described in Burroughs Patent No. 504,963 issued September 12, 1893. The said detent or latch performs a 20 dual function in that it provides a means to normally prevent displacement of the handle from the shaft and also constitutes a device tending to maintain the shaft and handle in 25 proper relative positions for operation. The last mentioned function is desirable because 30 an abnormal relative movement of the shaft and handle is permitted by the detent whereby to enable the detachment of the handle from the shaft for the customary purposes 35 in the art. The first described function of the locking detent or latch for the handle involves the use of a very heavy actuating spring for the detent to maintain it in a 40 peculiar engagement or interlocking connection with the shaft.

By my present improvements I aim to dispense with the need for the employment of the special detent means above referred to especially as regards the necessity of using 45 a heavy actuating spring for said detent. With this object in view I have devised a novel contrivance associated with any suitable detent means capable of normally preventing the displacement of the handle from 50 the operating shaft, which contrivance effec-

tively maintains the shaft and handle parts in relative positions such that the detent connection is effective, and additionally provides a buffer of a resilient nature for facilitating stoppage of movement of the handle 55 as the main operating shaft of the machine returns to normal after a transaction of the machine.

With the above and other detail objects in view an understanding of my invention will 60 be had upon reference to the following description and accompanying drawings in which—

Figure 1 is a horizontal sectional view through the side frame of an accounting machine, adjacent to which the handle is disposed and showing the connection between the handle and shaft and the positioning device of the invention;

Fig. 2 is a sectional view on the line 2—2 70 of Fig. 1;

Figs. 3 and 4 are detail sectional views bringing out more clearly the form of the detent plunger on the handle; and

Fig. 5 is a detail view of the manner in 75 which the pressure slide coacts with the handle.

Specifically describing the invention, 625 denotes the main shaft of an ordinary adding machine equipped with the handle or 80 lever B⁵⁰¹. This handle is held in place on the outer end of the shaft 625 by means of the spring-actuated detent plunger 557, the spring 623 of which is a comparatively light 85 spring and disposed in a lower hollow portion or socket formed at the lower extremity of the handle. The connection formed by the parts 557 and 623 is similar to that in the Burroughs patent previously referred to and admits of the detachment of the 90 handle by an abnormal rearward movement beyond the customary limit of such movement occurring during the use of the handle for ordinary transactions of the machine. Also said connection is effective to act posi- 95 tively in turning the shaft 625 on forward pull of the handle, but ineffective to force a restoring movement, the latter movement being controlled by the customary governor of such machines, not shown. While the de- 100

tachable connection between the handle and shaft as above referred to may be employed; it is to be understood that the improvements of this invention are not necessarily limited 5 to use with such particular form of connection. On the shaft 625 is provided the customary arm 625^a having connected therewith the strong normalizing or restoring spring 625^b, the latter being suitably anchored at one end to a stud 625^c on the base 10 of the machine.

On the lower part of the right hand frame section 900^R is mounted the spring-retracted pressure piece or slide 558 slidably 15 connected at 558^a to said frame and normally pulled by a spring A⁶⁹⁵ toward the shaft 625, the spring being connected by a hook 559 with the side frame aforesaid. The pressure piece 558 has a lateral projection 558^b bearing against the lower shoulder of the clutch projection 501^c of the socket of the handle. The action of the pressure piece 558 is to hold said clutch projection firmly in engagement at the upper shoulder 634^c with the clutch projection 634 pinned on the main actuator shaft 625. As heretofore constructed, it has been necessary to provide a very stiff spring 623 to actuate the detent plunger 557 so that the 20 latter through engagement with the bottom of the cross slot in the shaft 625 will serve to maintain the handle in its normal substantially upright position, and also serve as a stop for the same. By using the means 25 which has been just described, including the part 558, the spring 623 may be made comparatively light as its only function is to maintain the plunger 557 sufficiently engaged with the shaft 625 to prevent longitudinal 30 displacement. The members 558 and A⁶⁹⁵ are not only very effective to hold the handle in its normal upright position, but they provide a yieldable buffer or stop 35 means for stopping the handle at the end 40 of its return stroke in a manner which will be quite obvious.

Having thus described my invention, what I claim as new is:

1. In combination, an operating shaft, a 50 detachable handle therefor, means acting on the shaft for holding the handle in and returning the same to a normal position, a detent on the handle engaging the shaft to connect said parts for relative movement, and means other than said detent for holding the handle in its normal position relative to the shaft.

2. Means substantially as claimed in claim 1, wherein the last means comprises a pressure device separate from the handle and normally acting to hold the handle at a certain limit of movement relatively to the shaft.

3. Means substantially as claimed in claim

1, wherein the last means comprises a pressure device separate from the handle and normally acting to hold the handle at a certain limit of movement relatively to the shaft, and forming a yieldable stop for the handle.

4. In combination, an operating shaft, a detachable handle therefor, means acting on the shaft for holding the handle in and returning the same to a normal position, a detent on the handle engaging the shaft effective to enable the handle to move the shaft in one direction only, and a combined pressure piece and yieldable stop coating with the handle.

5. In combination, an operating shaft, a 80 detachable handle therefor, means acting on the shaft for holding the handle in and returning the same to a normal position, a detent on the handle engaging the shaft to detachably connect said parts, and a combined pressure piece and yieldable stop slidably adjacent to the handle and having a projection engaging the latter, and a spring normally acting on said pressure piece to hold the handle at a certain limit of its movement relatively to the shaft.

6. The combination of an operating shaft, a handle thereon and adapted for movement relatively thereto, a pressure device adjacent to said shaft and supported independently of the handle, and means acting on said pressure device whereby to cause the same to resiliently act upon the handle to hold the latter in a predetermined position relative to the shaft.

7. In combination, a shaft, an actuating handle detachably fitted to said shaft and movable with and independently in respect to the latter, and a resiliently-operated pressure piece engaging said handle to normally maintain the same in a predetermined position relative to the shaft, said pressure piece acting as a buffer stop co-operative with the handle.

8. In an accounting machine, the combination with an operating shaft, return means to normalize the shaft after actuation, of a yieldable buffer adjacent to said shaft, and a handle connected to operate the shaft and adapted for movement relative thereto, said handle having means co-operative with the buffer whereby the handle is normally maintained in a proper upright position upon the shaft ready for actuation.

9. In an accounting machine, the combination with an operating shaft, return means to normalize the shaft after actuation, of a yieldable instrumentality adjacent to said shaft, and an operating handle movable on said shaft and co-operative with the said instrumentality whereby the handle is held in a normal position relative to the shaft.

10. In an accounting machine, the combination with an operating shaft, return means to restore the shaft after actuation, of a yieldable buffer adjacent to said shaft, 5 a handle on said shaft and movable relatively thereto for purposes of attachment and detachment, said handle coöperative with the buffer whereby the handle is held in a normal position upon the shaft, and the buffer acts to cushion the movement of the handle with the shaft incident to restoring of the latter.

In testimony whereof I affix my signature.

AMOS H. HAWLEY.
